(57) **CLAIM**

The ornamental design for a decorated blanket, as shown and described.

DESCRIPTION

FIG. 1 is a perspective view of the decorated blanket showing our new design;

FIG. 2 is a front view of the blanket shown in FIG. 1;

FIG. 3 is a rear view thereof;

FIG. 4 is a left side view of FIG. 1;

FIG. 5 is a right side view of FIG. 1;

FIG. 6 is a top view of FIG. 1; and,

FIG. 7 is a bottom view thereof.

The dotted broken lines present within the design represent features that form not part of the claim. The parallel curved broken lines form the bounds of the claim and also form no part of the claim.

1 Claim, 5 Drawing Sheets
